UNITED STATES PATENT OFFICE.

EMILE FÉLIX GUÉRIN, OF PARIS, FRANCE.

PARQUET-FLOORING.

SPECIFICATION forming part of Letters Patent No. 350,457, dated October 5, 1886.

Application filed February 20, 1886. Serial No. 192,734. (No model.) Patented in England April 15, 1884, No. 6,388; in Belgium April 30, 1884, No. 65,001; in France July 29, 1884, No. 163,533, and in Austria-Hungary November 22, 1884, No. 52,873 and No. 53,959.

To all whom it may concern:

Be it known that I, EMILE FÉLIX GUÉRIN, of Paris, France, have invented a new and Improved Parquet-Flooring, of which the following is a full, clear, and exact description.

The object of my invention is to provide new and improved parquet-flooring which is simple in construction, does not show the heads of fastening screws or nails on its surface, and which can contract and expand without warping and throwing, and which flooring is comparatively inexpensive.

The invention consists in the construction and combination of parts and details, as will be fully described and set forth hereinafter, and then pointed out in the claims.

Reference is to be had to the accompanying drawings, forming a part of this specification, in which similar letters of reference indicate corresponding parts in all the figures.

Figure 1 is a plan view of my improved parquet-flooring. Fig. 2 is a cross-sectional view of the same on the line $x-x$, Fig. 1. Fig. 3 is a detail side view of parts.

The boards or strips A, forming the parquet-flooring, are provided with the grooves B in their ends, said grooves extending from one side edge of a board to the other side edge, and being about at the middle of the thickness of the boards. These end grooves serve to receive the metal tongues or strips C, which are secured to the side edges of the beams D, for supporting the boards A, or between the end edges of said boards and above the top edges of the beams. In the first case the tongues C are secured directly on the beams, and in the latter case they are connected, as presently described, to the beams D, supporting the ends of the boards, but do not rest on the same, as they are all together in the end grooves of said boards. Screws or nails E are passed through the metal tongues or strips C to hold them in place, said screws or nails passing into the tops of the beams D, as shown in Fig.

3. The tongues C are first fastened on the beams or held in place by the screws or nails, and then they are successively passed in between the said metal tongues in such a manner that the tongues enter the end grooves, B, of

the boards, and thus hold the said boards down on the beams. Those tongues C which are not embedded in the beams or not securely fastened are held from the tops of beams by those parts of the boards below the groove B, on which parts the said tongues C rest. Where the tongues C are embedded in the sides of the beams or otherwise securely fastened the tops of the beams are flush with the upper surfaces of the boards A. The boards A can be placed diagonally to the tongues C at right angles and to form any desired figures, as that does not interfere with the fastening device. When the tongues C project from the sides of the beams D, the ends of the boards A rest on the shoulders or offsets F of the beams.

The beams D may be secured on the usual floor-beams, or the tongues C may be secured on the usual floor-beams. No nail or screw heads are visible on the surface of the flooring. The flooring can shrink or contract without warping or throwing, and the boards can be pressed close together or loosened, according to the temperature.

The boards A can be removed and replaced by others very easily, and no nailing need be done.

The side edges of the boards A may be tongued and grooved in the usual manner, and the said boards may be of uniform or different widths.

I am aware of the existence of the floor-tile consisting of blocks arranged within a frame, the inner ends and sides of which frame and the edges of which blocks are provided with incisions or kerfs which receive a metal strip joining together the blocks and the frame.

Having thus fully described my invention, I claim as new and desire to secure by Letters Patent—

1. The combination, with the beams having shoulders or reduced at their upper edges and grooves in their sides, of the boards having in the ends grooves, and the plates fitting in the grooves of said beams and boards, said boards resting upon the shoulders of said beams, substantially as and for the purpose set forth.

2. The combination, with the intermediate and side beams, the side beams having shoul-

ders or reduced at their upper edges and grooves in their sides, of the boards having grooves in their ends, and the plates entering the grooves in, and uniting the abutting ends 5 of, said boards, and entering grooves in the other ends of said boards and the beams, said boards resting upon the intermediate beam at

their abutting ends and upon the shoulders of the side beams at their opposite ends, substantially as and for the purpose set forth.

EMILE FÉLIX GUERIN.
